CLAIM

The ornamental design for an intracorporeal artificial lung, as shown and described.

DESCRIPTION

FIG. 1 is a perspective view of the intracorporeal artificial lung installed on a truck;

FIG. 2 is a top view of the intracorporeal artificial lung installed on a truck;

FIG. 3 is a front view of the intracorporeal artificial lung;

FIG. 4 is a rear view of the intracorporeal artificial lung;

FIG. 5 is a left side view of the intracorporeal artificial lung;

FIG. 6 is a right side view of the intracorporeal artificial lung; and,

FIG. 7 is a bottom view of the intracorporeal artificial lung.
